Primary Examiner—Paula Greene(74) *Attorney, Agent, or Firm*—McCarter & English, LLP(57) **CLAIM**

The ornamental design for a dispenser, as shown and described.

DESCRIPTION

FIG. 1 is a perspective view of a dispenser showing our new design;

FIG. 2 is a front plan view of the housing of the dispenser of FIG. 1;

FIG. 3 is a left side plan view thereof;

FIG. 4 is a rear plan view thereof;

FIG. 5 is a top plan view thereof;

FIG. 6 is a bottom plan view thereof; and,

FIG. 7 is a right side plan view thereof.

The broken lines in the figures show structure that is not part of the claimed design, but rather show the environment in which the design is associated, or show portions of the article in which the design is embodied or applied to that are considered part of the claimed design.
